UNITED STATES PATENT OFFICE.

JESSE M. COFFIELD, OF BELLAIRE, OHIO, ASSIGNOR OF ONE-HALF TO
SAMUEL A. KIRKLAND, OF BELLAIRE, OHIO.

BENCH-VISE.

SPECIFICATION forming part of Letters Patent No. 745,001, dated November 24, 1903.

Application filed May 23, 1903. Serial No. 158,504. (No model.)

To all whom it may concern:

Be it known that I, JESSE M. COFFIELD, a citizen of the United States, residing at Bellaire, in the county of Belmont and State of Ohio, have invented a new and useful Bench-Vise, of which the following is a specification.

My invention is an improved vise, my object being to provide a simple, inexpensive, effective, and easily-manipulated bench-vise having a stationary jaw and a movable jaw having a sliding movement and which can be moved by hand to the article to be clamped, requiring but a minimum use of the clamping-screw to secure same in a clamped position.

A further object of my invention is to provide means whereby the movable jaw can be moved up to the article to be clamped by foot-power, thereby leaving both hands free to handle the article to be clamped until the movable jaw has closed upon it, and to provide means whereby the foot can hold the movable jaw clamped to the article until the operator has secured it by means of the clamping-screw.

A still further object of my invention is to provide means whereby the reversal of the clamping-screw by one or two turns will unlock a pawl-and-ratchet device and a weight will automatically slide the moving jaw to its normal distance from the stationary jaw.

My invention consists of an elongated base having a recessed stationary jaw thereon, a ratchet formed longitudinally along the center of the base, a movable jaw having a stem sliding on the base and working through the jaw, the stem being hollowed out and downwardly and rearwardly open, a block fitting in said stem and carrying a pawl engaging the ratchet, and a clamping-screw working in a threaded aperture in the block, means carried by the clamping-screw for forcing the pawl out of engagement with the rack-teeth when the block is moved slightly rearward, and means for automatically sliding the moving jaw from the stationary jaw when the pawl is disengaged.

My invention consists also in the novel features of construction and combination of parts hereinafter described, particularly

pointed out in the claims, and shown in the accompanying drawings, in which—

Figure 1 is a perspective view of my vise in position. Fig. 2 is a vertical longitudinal section, the clamping-screw and pawl being in elevation. Fig. 3 is a section on the line 3 3 of Fig. 2. Fig. 4 is a section on the line 4 4 of Fig. 2. Fig. 5 is a perspective view of the movable jaw and stem. Fig. 6 is a perspective view of the stationary jaw and base. Fig. 7 is a perspective view of the block. Fig. 8 is a perspective view of the pawl. Fig. 9 is a detail perspective view of the inner end of the clamping-screw. Fig. 10 is a detail perspective view of the tripper for operating the pawl.

In the drawings, A represents an elongated base widened intermediate its ends, so that it will solidly set on a bench or other support. Down the center of this base are formed a series of rack-teeth A', a smooth surface being left on each side of the teeth on which slides the movable stem B. Mounted on the base intermediate its ends is a hollow stationary jaw A², arching over a portion of the rack-teeth. An inner wall of the jaw A² is horizontally grooved at A³ for a purpose which will hereinafter appear, and on each side of the rack-teeth in advance of the jaw A² are slots A⁴, in which are mounted pulleys A⁵. The stem B is hollowed out, as shown at B', and carries a jaw B², movable with reference to the jaw A².

A block C is adapted to fit in the stem B and to slide within same on the base A. This block has a threaded perforation C'. Its lower face is recessed, as shown at C², and at its rear end two parallel lugs C³ project horizontally rearward. The block is also transversely apertured at C⁴, the aperture intersecting the recess C². A pawl C⁵, having a head C⁶, a beveled rear end C⁷, and an elongated slot C⁸, fits in the recess C², the head projecting in advance of the block and the rear beveled end resting between the lugs C³.

The pawl is loosely pivoted by a pin C⁹, passing through the aperture C⁴ and slot C⁸. The jaw B² has a bore B³, through which passes a clamping-screw D, its forward end being of the usual construction. Its rear threaded

portion works in the threaded aperture C' of the block C, and the screw terminates in a reduced threaded end D'. The tripper consists of a flat plate E, having an aperture E' and a central depending tooth E², beveled on its forward face. The aperture E' is of greater diameter than the screw D, and the plate slips and hangs loosely thereon, the tooth resting between the lugs C³ and contacting with the end C' of the pawl. A nut E³ fits over the end D', being held by a washer, and prevents the tripper-plate from slipping off the end. A portion of the front of the jaw B² is cut out and a wear-plate B⁴ is secured therein, the 15 clamping-screw turning on said plate.

A cord F is secured to the stem B in the rear of the stationary jaw and carried forward through the groove A³ and over the adjacent pulley A⁵, a weight F' being secured to its free end. A cord G is secured to the movable jaw and carried rearwardly over the other pulley A⁵ and at its lower end is secured to a pivoted treadle G'.

The operation of my device is as follows: 25 The tooth E² of the washer or trigger E, bearing on the end of the pawl at C', lifts the head of the pawl out of engagement with the teeth A', when the screw D is partially unscrewed, so as to cause the nut E³ to tend to wedge the 30 trigger E against the rear end of the block C. The weight F' holds the moving jaw away from the jaw A². By pressing the forward end of the treadle down with the foot the jaw B² is moved toward the jaw A², clamping the 35 article to be gripped. Pressure of the foot will hold the jaw firmly against the article, leaving both hands of the operator free to arrange the article between the jaws and turn the clamping-screw. A slight turn of the 40 screw will draw the block C forward, increasing the space between the block and the nut E³, relieving the rear of the pawl of pressure, and the head will fall by reason of its weight and prevent further forward movement of 45 the block. An additional turn of the screw will cause the jaw B² to firmly grip the article held between the jaws. When it is desired to separate the jaws, it is only necessary to turn the screw sufficiently to bring the block 50 C adjacent the nut E³, when the tripper will bear on the end of the pawl, lifting the head, and the weight will slide the jaw B² away from the jaw A². It will be obvious that a 55 spring can be employed in lieu of a weight and that the mechanism described may be applied to other forms of vises than a bench-vise.

Having thus fully described my invention, what I claim as new, and desire to secure by 60 Letters Patent, is—

1. A device of the kind described comprising an elongated base-plate having a series of rack-teeth formed thereon, a hollow, stationary jaw mounted midway the ends of said plate 65 and above the rack-teeth, a movable jaw slid-

ing on said base-plate and having a stem working through the stationary jaw, a pulley arranged adjacent the front of the base-plate, a cable secured to the stem of the movable jaw and passing over the pulley, a weight at the 70 free end of said cord adapted to draw the movable jaw away from the stationary jaw, means for counteracting said weight and drawing the movable jaw to the stationary jaw, and means for locking the movable jaw against 75 movement.

2. A device of the kind described comprising a base, having a recessed stationary jaw mounted thereon, the inner wall of said recess having a horizontal groove therein, and the 80 base being slotted in advance of the jaw and in alinement with said groove, a pulley in the slot, a movable jaw having a stem sliding on said base and extending through the stationary jaw, a cord secured to the stem in the rear 85 of the stationary jaw, and extending through the groove and over the pulley, and a weight secured to the free end of the cord.

3. A device of the kind described comprising a base having a recessed stationary jaw 90 mounted thereon, said base having a plurality of longitudinal slots formed therein in advance of the jaw, pulleys arranged in the slots, a movable jaw having a stem sliding on the base through the stationary jaw, a cord secured to the stem in the rear of one of the slots and passing over the pulley in said slot, a weight secured to the free end of said cord, a treadle pivoted below the jaws, and a cord secured at one end to the movable jaw, in advance of one of the pulleys and passing over said pulley, the lower end of the cord being 95 secured to the treadle.

4. A device of the kind described comprising a base-plate having a series of rack-teeth 105 formed thereon, a recessed stationary jaw mounted on the base-plate, a movable jaw having a stem sliding in said recess of the stationary jaw, said stem being recessed and downwardly open, a block sliding in said stem, the 110 said block having a longitudinal, threaded perforation and being recessed on its lower face, parallel lugs projecting rearwardly from the block, a pawl loosely pivoted in the recess of the block, a screw working in the threaded 115 perforation of the block, the said screw having a reduced threaded end to the rear of the block, an apertured plate fitting loosely on said screw, to the rear of the block, a beveled tooth on said plate adapted to bear on the rear 120 end of the pawl, and a nut on the reduced end of the screw adapted to bear on the plate and force the tooth of the plate into engagement with the pawl when the screw is partially unscrewed.
